Primary Examiner — Ramzi Almatrahi(74) *Attorney, Agent, or Firm* — Falk Ewers; Ewers IP Law PLLC(57) **CLAIM**

The ornamental design for a thermal imaging camera, as shown and described.

DESCRIPTION

FIG. 1 is a top perspective view of a thermal imaging camera showing our new design;

FIG. 2 is a bottom perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a rear plan view thereof; and,

FIG. 8 is a front plan view thereof.

The broken lines depict portions of the thermal imaging camera in which the design is embodied that form no part of the claimed design.
